1511 Kane St., Carlyle, Ill. 62231

Filed Mar. 8, 1968, Ser. No. 10,926

Term of patent 14 years

(Cl. D34—5)

The figure is a perspective view from above of a game board showing our new design.

The game board is flat and the underside is devoid of ornamentation.

The dominant features of our design reside in the portions shown in full lines.

The drawings are stippled to indicate color contrast.
We claim:

The ornamental design for a game board, as shown and described.
